UNITED STATES PATENT OFFICE.

JOSEPH E. JONES, OF WALTHAM, MASSACHUSETTS.

DIAPHRAGM ATTACHMENT.

1,415,360.

Specification of Letters Patent. Patented May 9, 1922.

Application filed June 18, 1920. Serial No. 389,927.

To all whom it may concern:

Be it known that I, JOSEPH E. JONES, a citizen of the United States, residing at Waltham, in the county of Middlesex and 5 State of Massachusetts, have invented certain new and useful Improvements in Diaphragm Attachments, of which the following is a specification.

This invention relates to diaphragm attachments, especially designed for use in connection with such diaphragm constructions as used upon the Edison phonograph.

Another object of this invention is the production of a very simple and efficient means 15 for attaching the cord to the diaphragm in such a manner as to permit the cord to be released from the diaphragm when so desired and replaced should occasion arise.

With these and other objects in view this 20 invention consists of certain novel construction, combination and arrangement of parts as will be hereinafter fully described in claims. In the drawing:

Figure 1 is a top plan view of the dia- 25 phragm.

Figure 2 is a bottom plan view thereof.

Figure 3 is a central transverse sectional view through the diaphragm.

Figure 4 is a top plan view of a modified 30 form of the diaphragm which will be known as the friction cone construction.

Figure 5 is a bottom plan view of the dia- 35 phragm attachment shown in Figure 4, and

Figure 6 is a central transverse sectional view through the diaphragm.

By referring to the drawings it will be seen that 1 designates the diaphragm which may be formed of any suitable or desired material or construction such for instance 40 as is employed upon the usual "Edison" type of reproducers employed upon phonographs and the like. A reinforcing disc 2 formed of cork or other suitable material is secured to the underface of the diaphragm disc 1 45 and a threaded plug 3 is passed through the center of the disc 2 as clearly shown in Figure 3. This threaded plug 3 is externally threaded and receives a cone 4, which is internally threaded as indicated at 5, so as to 50 permit the cone 4 to be firmly threaded upon the plug 3 and in this way hold the diaphragm disc 1 in firm engagement with the inner face 6 of the reinforcing disc 2. This cone 4 may be formed of celluloid, glass or 55 other suitable material without departing from the spirit of the invention.

A cord supporting shank 7 is seated within the tapering pocket of the plug 3 as clearly shown in Figure 3, and this shank 7 is provided with externally threaded extension 9, 60 which extension projects through the aperture 10 formed in the cone 4 and receives a nut 11 for the purpose of firmly binding the cone 4 in a set position against unthreading movement from the plug 3. The cord 65 12 is extended from the shank 7 and any suitable or desired connecting means may be carried by the cord for permitting the same to be readily attached to the needle carrying arm of the reproducer. 70

In Figures 4, 5 and 6 there is shown a modified form of the invention wherein the usual disc 1^a is employed having the reinforcing disc 2^a secured to the underface of the disc 1^a. A friction cone 3^a extends centrally through the disc 1^a and 2^a and this cone 3^a is provided with a laterally extending flange 13 upon its inner end for firmly holding the disc 2^a in engagement with the disc 1^a. This cone 3^a is provided with a 75 shoulder portion 14 and a reduced aperture formed near the inner end. A cord supporting shank 16 supports the cord 17 of the usual construction and this shank 16 is provided with an internally aperture 18 at one 80 end for the purpose of receiving the threaded shank 19 of the securing screw 20. A friction cone 21 fits over the cone 3^a and is provided with a substantially conical shaped socket 22 for frictionally receiving and gripping the cone 3^a as clearly shown 85 in Figure 6. The screw 20 is adapted to extend through the upper end of the cone 21 and fit snugly within the internally threaded aperture or socket 18 of the cone 3^a as shown 90 in Figure 6 for frictionally holding the cone 21 in firm engagement with cone 3^a and at the same time causing the lower end 23 to firmly bind the diaphragm disc 1^a in engagement with the adjoining face of the disc 2^a. 95

In the foregoing description it will be seen that a very simple means has been produced whereby the diaphragm disc 1 and 1^a may be firmly held in an assembled position so as to produce the desired results without the 100 necessity of holding the same in engagement with each other by the usual method such as wax or other soldering medium. It, of course, is obvious that should the cords 12 or 17 become broken, the same may be readily 105 replaced. It should also be understood that the means of attaching the cord to the dia-

phragm will prevent the cords from being accidentally detached from the diaphragm, thereby constituting a permanent and efficient securing means therefor. It has been 5 found by actual experience that the attachment of the cords to the diaphragm disc in the manner set forth, will not only increase the life of the diaphragm, but will also greatly increase the volume as well as im- 10 prove the tone.

It, of course, should be understood that certain detailed changes in mechanical construction may be employed without departing from the spirit of the invention so long 15 as these changes fall within the scope of the appended claims.

What I claim is:

1. A diaphragm attachment comprising a diaphragm disc, a threaded plug extending 20 through said disc a cone carried by said plug, a cord, a shank engaging said cord and fitting within said plug, a disc engaging flange clamping said disc in a set position, and means connected to said cord engaging shank

and engaging said cone for locking said cone 25 upon said plug.

2. A diaphragm attachment of the class described, comprising a diaphragm disc, a reinforcing disc secured thereto, an externally threaded plug extending centrally 30 through said reinforcing disc and diaphragm disc, a cone threaded upon said externally threaded plug, a cord engaging shank mounted within said plug and provided with a threaded extension projecting through said 35 plug and the upper end of said cone, and a nut threaded upon the outer end of said extension for firmly clamping said cone against movement of said plug, whereby said cone will firmly bind said diaphragm disc into 40 engagement with said reinforcing disc.

In testimony whereof I affix my signature in presence of two witnesses.

JOSEPH E. JONES.
